DATA SHEET HOLDER

George D. Cox, Philadelphia, Pa., assignor to
 Williams and Marcus Company, Philadelphia,
 Pa., a corporation of Pennsylvania

Application April 19, 1933, Serial No. 666,804

5 Claims. (Cl. 129—16.7)

This invention relates to holders for data sheets or cards; and it has reference more specifically to data sheet or card holders intended for accommodation, like letter folders, in drawers of office filing cabinets.

In the management of various businesses it is essential or desirable that separate data sheets or cards be kept for recording different transactions relating to each individual subject. An instance which may be cited as typical of the above is in connection with life insurance office management where several data sheets or cards are kept for each individual policy on which sheets or cards are separately recorded the name and residence of the insured, doctor's reports, premium payments, loans, etc. Heretofore, such data sheets or cards were kept in separate cabinets which were located in different office departments, so that the assembling of the complete complement of the data sheets or cards for ascertaining of full information with regard to any particular subject, or for the purposes of photographing or photostating when copies were required, entailed expenditure of considerable time on the part of clerks in charge of such files. Also under this system, the data sheets or cards soon become soiled through frequent individual handling, and were moreover likely to be misplaced or lost.

In the main, my invention is directed toward overcoming the above recited drawbacks, which desideratum I attain through provision of a thin compact flat transparent holder which lends itself to very economic manufacture; which affords a multiplicity of individually-accessible pockets for the several data sheets or cards employed for a particular subject; which is capable of being readily stacked or piled with others or of being interposed upright between others in a drawer of a filing cabinet; and which permits photographing or photostating of the data sheets or cards without necessitating their removal.

Other objects and attendant advantages will be manifest from the detailed description following of the attached drawings, wherein Fig. I is a perspective view of a data sheet or card holder conveniently embodying my invention in one form.

Fig. II is a vertical sectional view of the holder drawn to a larger scale and taken as indicated by the arrows II—II in Fig. I.

Fig. III is a fragmentary vertical detail sectional view taken as indicated by the arrows III—III in Fig. I.

Fig. IV is a fragmentary horizontal detail section taken as indicated by the arrows IV—IV in Fig. I.

Figs. V and VI are fragmentary detail sectional views corresponding to Fig. II and showing two different modifications of my invention.

Referring first to the embodiment of my invention delineated in Figs. I—IV of these drawings, the data sheet or card-holder there shown is of rectangular configuration and formed with 10 transparent side walls 10 and 11, which may be of any clear, pliant, flexible and tough tear-resistant sheet material like celluloid or cellulose acetate, the latter being preferred by virtue of its greater safety against fire and explosion. In 15 making up the holder, I double an elongated blank sheet of the transparent material upon itself with creation of a rounded fold along the bottom end of the holder as indicated at 12 in Figs. I and II, the line of fold being so ordered 20 as to predetermine slight projection of one end edge of the sheet above the other end edge. To close the folder at the top, I bend down the extended portion of the longer side of the sheet which constitutes the front wall 10 of the holder 25 as at 13 in Figs. I and II into marginally lapping relation with the free edge of the shorter side which constitutes the back wall of the holder, and secure the fold 14 to said back wall with a 30 suitable cementing medium which will render the juncture permanent as by localized fusion over the contacting areas. When the holder is to be stored upright with others, for example, in the drawer of a filing cabinet, in order to render its removal easy, I turn up the edge of the marginally lapping portion 14 at a slight angle as at 35 15 to provide a projection convenient of engagement by the finger-nails incident to withdrawing the holder from such drawer. As an alternative, I may form the edge of the lapping 40 margin 14a with a bead such as shown at 15a in Fig. V instead of turning up the edge as described in connection with Figs. I and II. When the folder is to be piled or stacked with others, or in instances where finger-nail projections are 45 not desired, the downfolded marginal portion 14 may be made flat throughout as shown at 14b in Fig. VI.

Either before or after folding of the transparent sheet in forming the jacket of the folder, I 50 interpose between the side walls 10, 11 at spaced intervals vertically of the folder, a number of narrow horizontal partitioning strips 16 (in this instance two) which may be of transparent material like said walls, or of an opaque material 55

having the same characteristics as regards flexibility, toughness and resistivity to tearing. These partitioning strips 16 I likewise secure to the side walls 10, 11 by aid of a cementing medium such as hereinbefore referred to in connection with the top edge fold 14. Along the vertical center of the holder, I unite the sides 10, 11 at intervals by spot denting them as at 17 in Figs. I, III and IV, with the aid of an appropriate tool for the purpose, there being in this instance two indentations 17 for each horizontal subdivision of the holder, one indentation being made from one side of the holder, and the other from the opposite side. However, these indentations 17 may, if desired or found convenient, all be made from one side of the folder, and in either case collectively form a central barrier or partitioning means, whereby, in conjunction with the horizontal partitioning strips 16, the holder is subdivided into two vertical rows of pockets 18 for reception of individual data sheets or cards such as conventionally indicated at 19. The pockets 18 of the respective vertical rows, it will be observed, are accessible from the opposite side edges of the holder; and said edges are formed with finger notches as at 20 which will permit grasping of the data sheets or cards 19 incident to removing the same.

From this detailed description it will be seen that my improved data sheet or card holder has all the attributes and affords all the advantages hereinbefore pointed out in the first part of the specification. The holders herein shown for convenience of illustration are in practice made ten 35 by ten inches and subdivided into six pockets adapted to accommodate data sheets or cards approximately three by five inches. I do not however wish to be considered as limited either to these proportions or to the number of pockets 40 shown since these considerations are subject to extensive variation in practice.

Having thus described my invention, I claim:

1. As a new article of manufacture, a flat flexible rectangular holder of the character described 45 for use in file cabinet drawers, having side walls formed by a folded sheet of transparent tear-resistant material with one end of the sheet overlapped upon and united to the other at the back of the folder to close the latter at the top and the edge of said fold-down portion bent outwardly to form a fingernail grasp for convenience of removing the holder from the file cabinet drawer, and partitioning means setting apart in the interval between the side walls a multiplicity of 50 separate pockets for as many different data

sheets or cards, said pockets being accessible for insertion and removal of the data sheets or cards from one side edge of the holder.

2. A data sheet or letter holder for filing cabinets in the form of a flat rectangular envelope 5 open at its side edges and comprising a folded quadrangular sheet of transparent tear resistant material like cellulose acetate with one end of the sheet lap jointed over the other along the top edge of the holder and formed with a longitudinal bead for the purposes of a finger nail grasp.

3. A data sheet or letter holder for filing cabinets, having the form of a flat rectangular envelope comprising a quadrangular sheet of stiff, 15 transparent, tear-resistant material like cellulose acetate folded upon itself with the side edges of the folds coincident and the end edges joined to each other; and coincident internesting spot indentations formed from the opposite faces of 20 the holder and connecting said faces at intervals to set apart pockets individually accessible for insertion or removal of the letters or data sheets through the open side edges of said holder.

4. A data sheet or letter holder for filing cabinets, having the form of a flat rectangular envelope comprising a quadrangular sheet of stiff, transparent, tear-resistant material like cellulose acetate, said sheet being folded upon itself 30 with the side edges of the folds coincident and the end edges joined to each other; and spot indentations connecting the opposite faces of the holder at intervals and setting apart pockets individually accessible for insertion or removal of 35 the letters or data sheets through the open side edges of the holder, said spot indentations being indented alternately from opposite faces of the holder.

5. A data sheet or letter holder for filing cabinets, having the form of a flat rectangular envelope comprising a quadrangular sheet of stiff transparent tear-resistant material like cellulose acetate folded upon itself with the side edges of the folds coincident, and with the end edges of 45 the sheet joined to each other; a number of horizontal vertically-spaced partitioning strips interposed between the side faces of the holder; and spot indentations connecting the opposite faces of the holder vertically adjacent the horizontal partitioning strips aforesaid to form, 50 jointly with said partitioning strips, two rows of pockets individually accessible from the open side edges of the holder.

GEORGE D. COX. 55
